UNITED STATES PATENT OFFICE.

ELIAS J. WOLGAMOOD, OF COLORADO CITY, COLORADO.

DOWELING DEVICE.

1,097,153.

Specification of Letters Patent.

Patented May 19, 1914.

Application filed March 14, 1910. Serial No. 549,126.

To all whom it may concern:

Be it known that I, ELIAS J. WOLGAMOOD, a citizen of the United States, residing at Colorado City, in the county of El Paso and 5 State of Colorado, have invented new and useful Improvements in Doweling Devices, of which the following is a specification.

My invention relates to doweling devices and more particularly to a simple, compact 10 and cheaply constructed device which may be easily transported from place to place together with other tools usually carried by a wood worker in the course of his trade.

I am aware that doweling tools similar to 15 mine in general construction are now in use upon lathes and other similar machines, but as my invention is not to be used in connection with any machine, but is a tool complete in itself and made so as to be easily transported from place to place, it is thought 20 these machine attachments do not in any way concern my present invention.

It is an object of my invention to provide 25 a small but efficient device to be used in connection with the ordinary brace and bit and provided with means for guiding the bit so that the latter will not be permitted to swerve and so produce any irregularity in the dowel hole.

Another object of my invention is to produce such a tool which will provide means 30 for making holes for dowel pins in two pieces of wood so that the holes are exactly corresponding with one another, being the same distance apart or located in any desired position in the wood.

A still further object of my invention is 35 the provision of simple means of adjustment so that the dowel holes may be placed any required distance apart without measuring and marking the location of the holes in the wood as is at present necessary.

A still further object is to provide such a tool as above pointed out which can be 40 adapted to receive bits of different sizes and can be used to make dowel holes in wood of various thicknesses, and which can be fastened in operative position by means of a suitable clamp or the like.

With the foregoing and other objects in 45 view, my invention consists of such details of construction and arrangement and combination of parts as will be hereinafter more fully described and specifically pointed out 50 in the claim.

In describing my invention in detail refer-

ence will be had to the accompanying drawings in which like characters denote like or corresponding parts throughout the several views and in which:

Figure 1 is a view in side elevation of my invention. Fig. 2 is a sectional view taken on line $x-x$ of Fig. 1. Fig. 3 is a view in side elevation showing the side opposite to that illustrated in Fig. 1. Fig. 4 is a top plan view more clearly disclosing the holes in the guides which holes are designed to receive the bits.

Referring to the drawings it will be seen that I provide a plate 1 of suitable size which plate is preferably made of metal, but which it will be understood may be made of any other material adapted to the purpose. Approximately one half of the plate 1 is covered with a second plate 2 which is detachably connected to the base plate by means of screws 3. The outer surface of the plate 2 may be roughened if desired in order that a better purchase upon the work being drilled may be obtained. A block 4 preferably of 70 chilled steel is placed upon one of the corners of the plate 1, one end of said block being in contact with an edge of the detachable plate 2. I have shown the block 4 in the drawings as being held in place by screws 5, 75

but it will be understood that said block may be cast integral with the plate 1 if so desired. Piercing the block 4 longitudinally and disposed nearer one side thereof than the other, is an aperture 6 which is of sufficient diameter to snugly receive the bit to be used in drilling the dowel hole. It will be seen that the size of the hole 6 will vary in different cases in order to accommodate bits of different diameters.

The numeral 7 designates an indicator formed upon the surface of the block 4 in order to disclose the exact position of the center of the aperture 6.

A guide-way 8 is mounted upon the plate 1 and extends from one side of the block 4 across said plate and terminates flush with one edge thereof. Said guide-way is dovetailed into the guide block 10 which is adjustable thereon. A scale may be indicated upon the guide-way 8 for the convenience of the worker in adjusting the block 10 in position. Approximately parallel to the guide-way 8 and disposed upon either side, thereof, are slots 9 formed in the plate 1, 105 said slots 9 terminating at one end short of the block 4 and at the other end short of

the edge of the plate 1. An aperture corresponding in diameter to the aperture 6 extends through the block 10 as shown at 11, the center of which aperture is indicated 5 by a line or other mark 12 made upon the block 10. The adjustable block may be fastened in any desired position by means of thumb screws 13 which are slideable in the slots 9 and which enter screw-threaded aper- 10 tures in the block 10.

It is thought that the operation of my invention will be readily apparent from the foregoing description. The plate 1 is first clamped against the face of a board or 15 plank, the edge of which is to be drilled in order to receive the dowel pins. This brings the plate 2 against the side of the board and disposes the blocks 4 and 10 in a position perpendicular to the edge of the board 20 which is to be drilled. The bit may then be inserted successively in the holes 6 and 11 and the dowel holes bored cleanly and without permitting the bit to swerve from its perpendicular position. After the holes 25 have been drilled in one piece of wood, the tool may be removed and clamped to the second piece without changing the adjustment of the guide blocks. It will be seen, therefore, that the holes in the two pieces 30 of wood will be exactly the same distance apart, and will both be drilled cleanly so that the two boards will be perfectly joined.

If the location for the dowel holes has 35 been marked upon one piece of wood, my tool may be clamped in place so that the indicators 7 and 12 exactly coincide with the marks. Thus the dowel holes may be drilled without trouble. If on the other hand it is desired to drill one hole and then 40 place the second hole a certain distance from the first this may be easily accomplished by means of the scale upon the guide-way 8. It is pointed out that several adjustable blocks similar to 10 may be placed upon the 45 guide-way if occasion should so demand, and if it is necessary to drill holes of different sizes, the blocks 4 and 10 may be removed and replaced by blocks having apertures of larger diameter.

50 The plate 2 is made removable in order that the tool may be used in connection with boards of different thicknesses. With the plate in place the device will receive two pieces of wood of a certain thickness and 55 may be operated to drill the hole exactly midway of the edges thereof, but if it is

desired to employ my invention in connection with a board of greater thickness, the plate may be removed in a short time and without inconvenience in order that the 60 dowel holes may be in correct position.

Heretofore when it was desired to join two pieces of wood by the use of dowel pins, it was necessary for the wood worker to lay off and mark each piece of wood so that the 65 holes were corresponding and then to drill the holes with the ordinary brace and bit. It quite often happens that the brace is not properly held in a vertical position or that the grain of the wood, or a knot therein, 70 causes the bit to vary from its perpendicular course so that when the pieces of wood are joined together their surfaces will be uneven and will not correspond. For this reason it has been found extremely difficult 75 to use the dowel joint, and at the same time, secure thorough work. By means of my invention doweling can be done very rapidly and with absolute accuracy and the device is so simple and cheap that the expense and 80 manufacture is insignificant.

It will be understood that slight changes in the construction and in the combination of the several parts may be resorted to without deviating from the spirit of my invention 85 providing such changes fall within the scope of the appended claim.

Having thus fully described my invention, what I claim as new and desire to secure by Letters Patent is:—

90 As a means for guiding bits in drilling dowel holes in the edge of a board, a plate adapted to be clamped against the side of a board with one portion of the plate projecting above the edge of the board, guide members each provided with a bore for guiding a bit, one of said guide members being fixed to the base plate in overhanging relation with respect to the edge of the board and with the axis of its bit-guiding bore at right 95 angles to the plane of the board edge, the other of said members being slidably mounted on that portion of the base plate projecting above the board edge to be adjusted parallel with the board edge, and means for 100 locking said adjustable sliding member in position, substantially as described.

ELIAS J. WOLGAMOOD.
